UNITED STATES PATENT OFFICE.

CHARLES F. PEASE AND CHARLES A. GREEN, OF CHICAGO, ILLINOIS, ASSIGNORS TO THE C. F. PEASE COMPANY, OF CHICAGO, ILLINOIS, A CORPORATION OF ILLINOIS.

SENSITIZED-PAPER-TREATING APPARATUS.

1,125,878.

Specification of Letters Patent.

Patented Jan. 19, 1915.

Application filed December 16, 1912. Serial No. 737,139.

To all whom it may concern:

Be it known that we, CHARLES F. PEASE and CHARLES A. GREEN, citizens of the United States, residing at Chicago, in the county of Cook and State of Illinois, have invented certain new and useful Improvements in Sensitized-Paper-Treating Apparatus, of which the following is a specification.

Our invention relates to new and useful improvements in machines for treating sensitized paper and particularly what is known as print paper after the same has been printed.

In the process of producing photographic prints having blue or black lines upon a white foundation it is customary to first pass the print paper through a printing machine. The coated surface of the print paper is next subjected to the action of a chemical solution. The next step in the process is to thoroughly wash the coated surface of the paper after the same has been treated with the chemical solution, to remove all traces of the same therefrom. It has been found that the length of time that the chemical solution should remain upon the coated surface of the print paper, varies with the character of the paper and the character or strength of the solution. In order that this length of time may be varied to suit the particular conditions, as above stated, the present invention provides novel means whereby the washing medium may be applied without loss and the washing apparatus moved toward or away from the device which applies the chemical solution to the coated surface of the paper, thus varying the length of time that such chemical solution will remain upon the coated surface of the paper before being removed by said washing apparatus. These are considered to be the most important features of the invention, as there is considerable waste of the washing medium in present apparatus and it has been found by experiments that it is impossible to make wholly satisfactory prints without providing some means to regulate the time for which the chemical solution remains upon the coated surface of the paper.

An important object of this invention is to provide means of the above mentioned character, which are simple in construction, reliable in operation and durable. 55

Other objects and advantages of this invention will be apparent during the course of the following description.

In the accompanying drawings forming a part of this application and in which like numerals are employed to designate like parts throughout the same, Figure 1 is an edge elevation of apparatus embodying the invention, a portion thereof being shown in section, Fig. 2 is a side elevation of the same, 65 and Fig. 3 is a plan view of the same.

In the drawings wherein for the purpose of illustration is shown a preferred embodiment of the invention, the numeral 1 designates a photographic printing machine, embodying a source of light and a bed plate over which the print or photographic paper 5 is caused to travel. This photographic printing machine is not shown, as the same forms no part of the present invention. 75

Connected with the rear portion of the printing machine 1 at each side thereof is a horizontal support or bracket 7, between which are mounted spaced horizontal rods or rolls 8 and 9, there being two of such supports or brackets. The print paper 5 passes under and supports a lower roll 10, having each end thereof provided with a flange, as shown. 80

A bracket 11 connected with the printing machine 1 serves to support the tank 16 hereinafter referred to. The print paper 5 passes above and in engagement with horizontal rods or rolls 8 and 9, as shown. 85

The numeral 12 designates means for applying a chemical solution, to the coated surface of the paper 5. This chemical solution applying means may be of any well known or preferred type. As an example of such means, we have shown a pipe 13 90 which is perforated upon its lower side, to spray the chemical solution upon or in proximity to a transverse depression element 14, from which such chemical solution is supplied in a continuous sheet or film upon the 100 coated surface of the print paper. This chemical solution passes into a catchment

basin 15, which is longer than the width of the print paper 5.

It is thought that no further description of the chemical solution applying means is necessary, as the same will not be claimed specifically or *per se* in this application. Such chemical solution applying means is however claimed separately in Patent No. 1,085,820, granted under date of February 3, 1914, the application maturing into which was filed Dec. 16, 1912, Serial No. 737,138. After the chemical solution is fed upon the coated surface of the paper 5, the same is caught in the catchment basin or receptacle 15, and is collected in a tank 16.

After the print paper 5 passes about the rod or roll 9 the same travels downwardly in proximity to washing apparatus 17, which forms a very important part of this invention. Such washing apparatus includes a catchment receptacle 18, provided upon each end thereof with an apertured lug or ear 19, which is slidably mounted upon a stationary vertical guide rod or track 20. These guide rods or tracks have their upper ends connected with the ends of the brackets 7. This catchment receptacle is considerably longer than the width of the widest print paper to be run through the machine, thus making it possible to pass print paper of various decreased widths through the machine.

The numeral 21 designates a spray device or pipe, provided with perforations throughout its entire length, and which is connected at each end thereof with an ear 22 carried by the catchment receptacle 18. The pipe 21 is of substantially the same length as the catchment receptacle, or perhaps a little shorter, and is therefore longer than the width of the widest print paper to be run through the machine. By this construction it is unnecessary to provide means to shorten the spraying area of the pipe 21, when passing narrower print paper through the machine. The water or other liquid spraying through the perforations in the pipe 21, laterally of and beyond the print paper, is caught in the catchment receptacle 18.

A water supply pipe 23 is connected with the perforated pipe 21, as shown. The catchment receptacle 18 is vertically movable and it is obvious that the perforated pipe 21 will move with the same.

Means are provided whereby the catchment receptacle may be raised and lowered, the same preferably comprising a sprocket chain 24, connected with the receptacle 18, as shown at 25. The sprocket chain 24 passes about upper and lower sprocket wheels 26 and 27, as shown.

Rigidly connected with the upper sprocket wheel 26 is a ratchet wheel 28, carrying a handle 28^a, and adapted to be normally en-

gaged by a holding pawl 29. It is thus seen that by moving the pawl 29 out of engagement with the ratchet wheel 28, the catchment receptacle 18 will descend to increase the distance between the same and the chemical solution applying means 12. By turning the ratchet wheel 28, the catchment receptacle 18 together with the perforated pipe 21, may be elevated or moved nearer the chemical solution applying means 12. The pawl 29 and ratchet wheel 28 serve as means to hold the washing apparatus in adjustment at different distances from the chemical solution applying means.

The operation of the entire system is as follows:—Assuming that the washing apparatus 17 has been vertically adjusted so that the same is at a proper distance from the chemical solution applying means 12, the print paper 5 is fed into the printing machine and travels longitudinally, as indicated by the arrow. When the print paper is passing through the chemical solution applying means 12, the same has its coated surface subjected to the action of the chemical solution. This chemical solution is thoroughly removed by the washing apparatus 17.

It is to be understood that the form of our invention herewith shown and described is to be taken as a preferred example of the same and that certain changes in the shape, size and arrangement of parts may be resorted to without departing from the spirit of the invention or the scope of the subjoined claims.

Having fully described our invention, we claim:—

1. In an apparatus of the character described, guide means for print or photographic paper when the same is being moved longitudinally, means for applying a chemical solution to the paper, washing apparatus to remove the chemical solution from the paper and means to vertically move the washing apparatus toward and away from the chemical solution applying means and positively lock the same in adjustment at the desired vertical position.

2. In an apparatus of the character described, guide means for print or photographic paper when the same is being moved longitudinally, means for applying a chemical solution to the paper, washing apparatus to remove the chemical solution from the paper, means to move the washing apparatus toward and away from the chemical solution applying means, and means to positively hold the washing apparatus in adjustment at different distances from the chemical solution applying means.

3. In an apparatus of the character described, means for applying a chemical solution to print or photographic paper, washing apparatus to remove the chemical so-

lution from the paper and vertically movable toward and away from the chemical solution applying means, means to guide the washing apparatus during the movement thereof, and means to hold the washing apparatus in adjustment at different distances from the chemical solution applying means.

4. In an apparatus of the character described, means to guide the print or photographic paper during its longitudinal travel, chemical solution applying means disposed near the paper, guide rods having corresponding ends thereof disposed near the chemical solution applying means, washing apparatus to travel longitudinally of the guide rods, means comprising a sprocket chain and sprocket wheels to move the washing apparatus, and means to normally hold the washing apparatus against movement in one direction.

5. In an apparatus of the character described, means to guide print or photographic paper during the longitudinal movement thereof, guide rods, a catchment receptacle slidably mounted upon the guide rods, means to move the catchment receptacle longitudinally of the guide rods, a washing apparatus connected with the catchment receptacle for movement therewith, and means disposed near corresponding ends of the guide rods to supply a chemical solution to the coated surface of the paper.

35 6. In an apparatus of the character described, upstanding guide rods, a catchment receptacle mounted therebetween, lugs formed upon the ends of the catchment receptacle and having openings formed therethrough to receive the guide rods, a perforated pipe carried by the catchment receptacle, upper and lower sprocket wheels, a sprocket chain engaging the upper and lower sprocket wheels and attached to the catchment receptacle, a ratchet wheel connected with the upper sprocket wheel for rotation therewith, a holding pawl disposed to engage the ratchet wheel, and means disposed near the ratchet wheel for applying a chemical solution to the paper.

7. In apparatus of the character described, the combination with a supporting structure, of paper guide means connected therewith, chemical solution applying means connected with the supporting structure and arranged in proximity to the paper guide means, a perforated conduit extending transversely of the paper to supply a washing liquid thereto and movable toward and away from the chemical solution applying means, and a catching receptacle arranged upon the opposite side of the paper in proximity to the perforated conduit and connected with the perforated conduit to support the same and move therewith.

8. In apparatus of the character described, the combination with a supporting structure, of paper guide means mounted thereon, chemical solution applying means connected with the supporting structure and arranged in proximity to the paper guide means, substantially vertically arranged guides, a catching trough connected with the guides and adapted to move longitudinally thereof toward and away from the chemical solution applying means and to occupy a position near and upon one side of the paper, a perforated conduit extending transversely of the paper upon the opposite side thereof and connected with the catching receptacle to be supported thereby and moved therewith, and means to vertically move the catching receptacle.

9. Apparatus for applying a liquid to print or like paper, comprising paper guide means, spraying means extending transversely for the full width of the path of travel of the paper to apply the liquid thereto, and a catchment receptacle disposed in proximity to said spraying means and on the opposite side of the path of travel of the paper, to receive the portion of the liquid not intercepted by the paper, said receptacle extending approximately parallel with the spraying means and being at least of equal length therewith.

10. Apparatus for applying a liquid to print or like paper, comprising a perforated tube extending transversely for the full width of the paper and disposed to one side of the same, a catchment receptacle disposed upon the opposite side of the paper and extending transversely thereof for the full width of the same and being at least of equal length with the perforated tube, and means to guide the paper during the longitudinal travel of the same.

11. An apparatus for applying a liquid to print or like paper, comprising a perforated tube extending transversely for the full width of the paper and disposed to one side of the same, a catchment receptacle disposed upon the opposite side of the paper and extending transversely thereof for the full width of the same and being at least of equal length with the perforated tube, means to raise and lower the perforated tube and catchment receptacle, and means to guide the paper during the longitudinal travel of the same.

12. In apparatus of the character described, a supporting structure, paper guide means mounted thereon, chemical solution applying means connected with the supporting structure and arranged in proximity to the paper guide means, a catching receptacle arranged transversely of the paper upon one side thereof and adapted to extend at both ends beyond the edges of the paper for a substantial distance, means

4
whereby the catching receptacle may be moved toward and away from the chemical solution applying means, and a perforated conduit arranged upon the opposite side of the paper, connected with the catching receptacle to be supported and moved thereby, and being substantially shorter than said catching receptacle.

In testimony whereof we affix our signatures in presence of two witnesses.
